UNITED STATES PATENT OFFICE.

HARRY M. BIGELOW, OF MILWAUKEE, WISCONSIN.

DESIGN FOR A MIXER.

59,702.

Specification for Design.

Patented Nov. 22, 1921.

Application filed January 10, 1921. Serial No. 436,373. Term of patent 7 years.

To all whom it may concern:

Be it known that I, HARRY M. BIGELOW, a citizen of the United States, and a resident of the city of Milwaukee, in the county of Milwaukee and State of Wisconsin, have invented a new and original Design for Mixers, of which the following is a specification, reference being had to the accompanying drawing, forming part thereof.

Figure 1 shows a side view of my new invention, and Fig. 2 is an end view thereof.

The device is designed for mixing butter or similar substances, such device being substantially triangular in any cross-section, and provided with a flat face 10 upon one

of its sides, and a curved or rounded face 20 upon the other side. The handle is attached to the third side or base 30 of the triangular member.

I claim:

The ornamental design for a mixer, as shown.

In testimony whereof, I have signed my name at Milwaukee, this 8th day of January, 1921.

HARRY M. BIGELOW.
